UNITED STATES PATENT OFFICE.

KATHRYN GOETZ, OF BROOKLYN, NEW YORK.

DESIGN FOR A LAMP.

44,304.

Specification for Design.

Patented July 8, 1913.

Application filed February 10, 1911. Serial No. 607,870. Term of patent 3½ years.

To all whom it may concern:

Be it known that I, KATHRYN GOETZ, a citizen of the United States, residing in the borough of Brooklyn, in the county of Kings and State of New York, have invented a new, original, and ornamental Design for Lamps, of which the following is a specification, reference being had to the accompanying drawing, forming part thereof.

The figure is a front elevation of a lamp showing my new design.

I claim:

The ornamental design for a lamp, as shown.

KATHRYN GOETZ.

Witnesses:

THOMAS A. HILL,
LOUISE ENDERLE.
